FASTENING MEANS

Arthur E. McNabb, Monessen, Pa., assignor to
 Pittsburgh Steel Company, Pittsburgh, Pa., a
 corporation of Pennsylvania

Application November 4, 1938, Serial No. 238,727

4 Claims. (Cl. 72—120)

This invention relates to fastening means, and more particularly is concerned with wire clips for fastening wire fabric lath, or the like, to furring bar or similar supports.

Heretofore, various types of wire clips have been provided for securing paper-back wire fabric lath to furring supports. These clips while satisfactory in many uses are open to certain objections. For example, some of the clips are expensive to manufacture and are difficult to secure in fastening position. Specifically, no wire clip has been provided, so far as I am aware, which can be secured in place with one hand thereby leaving one hand of the builder free to hold the fabric. Moreover, many prior types of wire clips when fastened in place do not provide adequate strength.

It is the general object of my invention to provide an improved wire clip for fastening metal lath, for example, paper-back wire fabric lath, to furring bars or similar supports.

Another object of my invention is the provision of an inexpensive, light weight but strong and sturdy wire clip whereby wire fabric or the like can be quickly and securely fastened to a desired support.

Another object of my invention is the provision of a wire clip for securing sheet material to a furring bar or other support which clip can be readily fastened in place by one hand of the operator while he is employing the other hand to support the sheet material or perform any other desired operation.

The foregoing and other objects of my invention are achieved by the provision of a wire clip for securing metal lath or the like to a furring support which clip comprises an elongated wire body generally having a bend therein adapted to engage resiliently with the fabric to be supported. The body is formed with a hook on one end which is adapted to hook around the furring support, and an eye on the other end of the body through which the hook of the next adjacent clip is adapted to be passed so that one hook supports the ends of two adjacent clips. Each eye of my improved clip has means associated therewith for temporarily holding the eye end of the body adjacent the fabric until the hook of the next clip can be passed through the eye.

Stated in combination form, my improvement comprises paper-back wire fabric lath, furring bar supports for the lath, wire clips securing the lath to the furring supports, each of said clips comprising a wire body lying against the lath on the side opposite the furring bars and a hook

on one end of the wire body and extending around a furring bar. The other end of each wire body is provided with an eye and the end of the eye has a leg secured thereto which extends substantially at right angles to the wire body through the fabric to the back thereof so that the leg lies substantially in the plane of the fabric. The hook on the end of one wire clip extends through the eye on the next adjacent clip and moldable plastic covers one side of the fabric and buries the clips.

For a better understanding of my invention, reference should be had to the accompanying drawing wherein Fig. 1 is a longitudinal sectional view through a ceiling including wire fabric lath which is secured in place in accordance with my invention; Fig. 2 is a cross-sectional view taken on the line II—II of Fig. 1; Fig. 3 is a plan view of my improved wire clip; Fig. 4 is a side elevation of my improved clip; and Fig. 5 is an end view of the clip.

While the improved clip of my invention may be employed in a number of fastening or securing capacities it is particularly adapted to secure paper-back wire fabric, such as manufactured under the trade name "Steeltex," in place on a wall or ceiling, and it has been so illustrated in the drawings in this capacity and will be so described.

Specifically, the numeral 10 indicates generally a paper-back wire fabric lath which is placed against furring supports 12 and which is held in this position by wire clips, indicated as a whole by the numeral 14. A moldable plastic 16, such as plaster or the like, is coated over the outside of the wire fabric lath 10 and buries the clips 14 in the completed ceiling, as will be understood.

Having particular reference to the wire clips 14, each comprises, as best seen in Figs. 3 to 5, an elongated body portion 20 made of a single piece of wire and usually at least six inches in length. A convenient length is eight inches. The body portion 20 is formed with a bend or offset near its center so that the body portion comprises two parts which join each other at an angle somewhat less than 180 degrees. Preferably the bend is made about one-quarter of an inch in height and is on the side of the clip which engages with the fabric in the fabric securing operation. The purpose of the bend is to provide a resilient portion on the body which engages with the fabric and urges the fabric into tight relation with the furring bar support therefor.

A hook is formed on one end of the body portion 20 which hook is adapted to extend around a furring bar support, as thus shown in Fig. 2. The hook generally takes the form of a leg portion 22 which extends at right angles to the body portion 20 of the clip and in a direction perpendicular to the plane of the fabric to be secured in place. The leg portion 22 has a limb portion 24 formed on its end which limb portion 10 extends at right angles to the leg portion and in a direction substantially perpendicular to the body portion of the clip. The end of the limb portion 24 has an arm portion 26 secured thereto which is substantially parallel with the leg portion but which extends somewhat out of the plane defined by the leg and limb portions 22 and 24 and in a direction away from the body portion 20 of the clip. This structure facilitates the placing of the hook over the furring bar and permits the arcuate movement of the clip as hereinafter described. The end of the arm portion 26 is cut to form a sharp point which is to adapt the hook so that it can readily pierce the paper back of the wire fabric lath.

25 The other end of the wire body 10 is formed with an eye, indicated as a whole by the numeral 30. The eye 30 lies in a plane substantially parallel to or coincident with the wire fabric to be supported by the clip and to the end of the eye 30 is secured a leg portion 32 which extends at substantially a right angle to the body portion 20 and substantially but not quite in the plane of the fabric to be supported by the clip. As best seen in Fig. 5, the leg portion 32 extends at an angle of usually between 5 and 20 degrees with the plane of the fabric to be supported so that it makes what might be termed a small angle with the clip. The end of the leg portion 32 is also pointed to facilitate pushing it through the paper back of the wire fabric lath.

40 My improved clip as just described in detail is conveniently and preferably made from a single length of wire so that the body, leg, limb, arm, and eye portions are all integral.

45 In the use of my improved clip the operator or builder holds the wire fabric lath against the furring bar support with one hand and with the other hand threads the hook end of the clip through the paper fabric of the lath and up and around the furring bar support so that the hook end of the clip is securely locked in position as will be understood. The operator now pushes the eye end of the wire clip with an arcuate swinging movement of the body of the clip about the hook as a pivot point to pierce the leg 32 through the paper back of the wire fabric. This movement is continued to bring the eye substantially into alignment with the furring bar. The point in the paper fabric through which the leg 32 is punched is selected to be quite near to the furring bar so that the arcuate movement of the clip after punching, and to bring the eye into alignment, does not tear the paper.

50 The arcuate or swinging movement of the wire clip also serves to position the outer end of the leg 32 behind the wire fabric, as best seen in Fig. 2. This entire operation can be performed by the operator's one hand while the other hand is holding the fabric in position against the furring bar support. The leg 32 on the eye 30 thus serves as means for temporarily holding the eye end of the wire clip in position and the bend or offset in the body portion 20 of the clip acts to resiliently 55 position the clip during and after the movement of the leg 32 through the fabric.

55 Now the operation is repeated to position a second wire clip in securing relation. The second wire clip taken by the operator is manipulated in his one hand while still holding the fabric so that the hook portion of the clip is threaded through the eye 30 of the preceding clip and the hook is manipulated to swing it around the furring bar support 12. When the hook on the second or next adjacent wire clip is in locking or supporting relation with the furring bar it will be seen that the hook serves not only to support its end of the wire clip 14 but in addition acts to hold up or position the eye end of the preceding wire clip. The eye end of the second wire clip is moved in an arcuate manner as before to pierce the leg 32 through the paper and wire fabric and thereby hold the clip in position and leave the hand of an operator free to pick up still a third wire clip.

60 The securing of the clips as just described is continued until a whole string of interlocked and connected wire clips is positioned along the whole length of wire fabric to be secured in place. The eye end of the last clip is secured in place against the furring bar by any suitable means, as for example, a wire or similar tie 34. Thus the series of clips forms a chain across the face of the fabric and provides a continuous support for the fabric from end to end.

65 It is believed that the objects of my invention have been fulfilled by the provision of the combination and the improved wire clip herein specifically illustrated and described. Suffice it to say that the improved fastening clip of my invention is inexpensive, easily made, and can be readily utilized by the ordinary laborer or construction man to rapidly and strongly secure paper back wire fabric lath or the like to a furring or other support. It can be snapped into position by one hand of a single operator which leaves his other hand free to hold the fabric or for other work.

70 In accordance with the provisions of the patent statutes I have specifically illustrated and described one particular form of my invention. However, it will be understood that my invention is not limited thereto or thereby but is defined in the appended claims.

75 I claim:

1. A wire clip for securing metal lath or the like to a furring support comprising an elongated wire body, a hook on one end of the body adapted to hook around the furring support, an eye on the other end of the body and through which the hook of the next clip is adapted to be passed so that one hook supports the ends of two adjacent clips, and means associated with the eye for temporarily holding the eye end of the body adjacent the fabric until the hook of the next clip can be passed through the eye.

2. A wire clip for securing metal lath or the like to a furring support comprising an elongated wire body having a bend therein adapted to engage resiliently with the fabric to be supported, a hook on one end of the body adapted to hook around the furring support, an eye on the other end of the body and through which the hook of the next clip is adapted to be passed so that one hook supports the ends of two adjacent clips, and means associated with the eye for temporarily holding the eye end of the body adjacent the fabric until the hook of the next clip can be passed through the eye.

3. A wire clip adapted to secure paper-back wire fabric lath or the like to furring bars or

- similar supports comprising a wire body portion formed with a bend or offset near its center portion and in a direction adapted to engage with the fabric, a locking leg portion formed integrally with one end of the body portion and adapted to hook around a furring bar, an eye formed integrally with the other end of the body portion, and a leg formed integrally with the end of the eye and adapted to extend at a relatively small angle through and to the back of the plane of the fabric when supported.
4. A wire clip adapted to secure paper-back wire fabric lath or the like to furring bars and comprising an elongated wire body having a bend therein near the center with the two parts of the body making an angle of a few degrees less than 180° with each other, an integral right angle leg

portion at one end of the body and extending in the same direction as the bend in the body, an integral right angle limb portion formed on the end of the leg portion and extending substantially in a plane perpendicular to the body, an integral right angle arm portion formed on the end of the limb portion and extending at a slight angle to the said plane and away from the body portion, an eye formed integrally on the other end of the body portion and lying in a plane substantially perpendicular to the leg portion, and an integral extension on the end of the eye and positioned substantially at right angles to the body but rising out of the plane of the eye on the leg portion side thereof.
